UNITED STATES PATENT OFFICE.

JAMES R. LEWIS, OF CHICAGO, ILLINOIS, ASSIGNOR, BY MESNE ASSIGNMENTS, TO INLAND ACCESSORIES MANUFACTURING COMPANY, OF CHICAGO, ILLINOIS, A CORPORATION OF ILLINOIS.

RELINING DEVICE FOR BRAKE BANDS AND THE LIKE.

Application filed October 2, 1920. Serial No. 414,322.

To all whom it may concern:

Be it known that I, JAMES R. LEWIS, a citizen of the United States, residing in Chicago, Cook County, Illinois, have invented certain new and useful Improvements in Relining Devices for Brake Bands and the like, of which the following is a specification.

My invention relates to means for applying a soft and flexible lining, such as leather or fabric, upon the metallic band constituting part of the braking or transmission apparatus of automobiles.

When the soft and flexible lining of such brake bands becomes worn out the practice heretofore has been to reline the bands by first cutting off the old rivets by a hand hammer and chisel and then riveting the new lining in position by a hand hammer operation, a method which is slow and expensive and unless done with considerable skill the work is not satisfactory through failure properly to clinch or turn over the rivet ends to get them well below the surface of the lining, and because of other irregularities incident to hand-tool work.

The present invention has for its chief object the provision of a relatively small machine, of simple, strong and few parts, in the use of which the rivet-cutting and riveting operations may be expeditiously and cheaply performed, and whereby at the same time a better and more satisfactory result will be attained than according to the older practice pointed out.

In the accompanying drawings, which form a part of this specification, Figure 1 is a perspective of the machine complete as adapted for riveting the lining to the brake band shown; Fig. 2 is an enlarged medial fragmentary section showing the plunger and its associated rivet-holding clip; Fig. 3 is an enlarged detail in medial vertical section showing the end of the plunger and the clip viewed at right angles to the position thereof shown in Fig. 2; Fig. 4 is a horizontal section on the line 4-4 of Fig. 3; Fig. 5 is a sectional view showing the anvil used in the riveting operation, the brake band being shown in cross sectional view. Figs. 2 and 5 together show the co-operative relationship of the plunger and anvil. Fig. 6 is a longitudinal vertical section through the anvil and its adjusting

means; Fig. 7 is a view like Fig. 6 and 55 shows the anvil in its elevated position of adjustment. This figure also shows how the anvil spreads and turns the ends of the rivet. Fig. 8 is a medial vertical section showing the substitution of elements to constitute the device a rivet cutter, the several parts being shown in operative position in the act of severing the lining from the band; and Fig. 9 is a fragmentary sectional view of the base of the frame and a top 60 65 plan of the anvil used in the rivet cutting operation.

Referring to Fig. 1 the device illustrated includes an upright main frame 15, in the form of a casting, having a forward integral lug or extension 16 bored to accommodate 70 slidably the plunger 17, an operating handle or lever 18 being pivoted at 19 upon the upper end of the frame. The lever 18 has an offset or bell-crank extension at 20 75 bifurcated to accommodate the end of the link 21 pivoted to the extension 20 at 22. The other end of the link 21 is pivoted at 23 to the upper end of the plunger 17. The plunger 17 has a reduced part 80 17^a, and the hole 25 in which the plunger moves has a correspondingly reduced part at 25^a (Fig. 2) whereby a space 26 is provided to accommodate the compression coiled spring 27 the action of which is to 85 elevate the plunger when the downward pressure is removed therefrom by releasing the lever 18.

The lower end of the plunger is cylindrically bored at 30 to accommodate the cylindrical stem 31 of the riveting head, Figs. 1, 2 and 3, or the cylindrical stem 32 of the cutter shown in Fig. 8, a set screw 33 being adapted to hold the stem firmly in its seat.

The riveting head shown in Figs. 1, 2 and 3 includes the stem 31 mentioned, upon which is slidably mounted a collar-like part 35, there being a pair of flat spring metal extensions 37 diametrically oppositely 100 disposed and rigidly held upon the collar 35, each of which springs 37 carries a foot 38 having an inclined surface 39, these feet 38 normally bearing against the lower edge of the stem 31. The end of the stem is 105 slightly hollowed or dish-shaped, as indicated at 40, Fig. 3, to accommodate the convex head of the split rivet 41, and when

the rivet head is in the position there shown the feet 38 extend a short distance under the head and hold the rivet upon the stem 31. This stem 31 constitutes an extension 5 of the plunger, and is the hammer or pressure-delivering part of the device. A coiled expansion spring 42 is positioned between the end of the plunger stem 17^a and the collar 35. From Figs. 1 and 2 it will be seen 10 that the collar 35 is held in position by a pin 36 which is rigid with the stem 31 and extends loosely in a slotted opening 44 in the collar 35, the construction enabling the stem 31 to move some distance relative to 15 the collar and as far as desired, while the pin remains in the slot 44. In practice this distance is about one-eighth of an inch and its advantage is had at such places as the hole 45, Fig. 1, in the brake band clamping device, which hole 45 is in some cases large 20 enough to accommodate the head of the rivet and the end of the stem 31 and enables the head of the rivet to be applied to the steel band 46 notwithstanding the additional 25 thickness of metal there. In such case when the feet 38 strike the part 65 the collar 35 stops in its downward movement, but the stem 31, pushing the rivet ahead of it, continues its movement about one-eighth of an 30 inch. When a rivet is being applied to the brake band (consisting of the steel band 46 and the flexible lining 47) as shown in Fig. 1, the operation of the handle causes the rivet 41 to enter the hole 48 in the steel band, and when the feet 38 come into contact with the steel band 46, the feet are 35 forced apart through the operation of the slanting surfaces 39 overlying the end of the stem 31 and the stem forces the head of the rivet firmly against the top surface 40 of the band.

The rivet 41 makes its own way through the flexible lining 47 and thereupon engages 45 the top surface of the anvil 50, which is formed with an upstanding tapering-sided and substantially conical projection 51 surrounded by an annular depression or groove 52. Pressure upon the head of the rivet 41 causes its legs to be separated by the projection 51, and the recess 52 bends around the 50 ends of the legs of the rivet, the beginning of the operation being shown in Fig. 7. When the stroke of the operating lever 18 is completed and a final sharp pull made 55 upon it both rivet legs are turned over as shown by the one leg 53 in Fig. 8, the legs being forced into the soft fabric well below its wear surface shown at 54 in that figure. For the next operation another rivet 60 is inserted by hand at the end of the plunger by sliding it laterally into position with its rim edge held by the feet 38.

The frame 15 has a forward integral extension 55 constituting a base or support for 65 the anvil 50, and this projection 55 is bored

coaxially with the plunger to receive the stem 57 of the anvil head 50. The lower end portion of the hole 56 is threaded to receive the adjusting screw 58 having the lock nut 59 thereon. The anvil stem 57 has 70 its end formed with a step or downward projection 60 on one side thereof, the end of the stem therefore having also a relatively high side 61, each side 60 and 61 being defined by a plane 62 which is on diametric 75 lines through the stem 57. The adjusting screw 58 is correspondingly provided with a stepped-up projection 63 providing a relatively low side 64, and the stem and screw interfit with each other in one position of 80 adjustment as shown by Fig. 6.

It is here pointed out that in some forms of brake band construction met with in repair practice it is necessary to use rivets of two different lengths on the same band, 85 namely in such cases as where the brake band clamping part 65, Fig. 1, has a hole at 45 which is large enough for the stem of the rivet but is not large enough to receive the head of the rivet as in other cases herein- 90 referred to.

Where the longer rivet is required the anvil head 50 will be in its relative position as shown by Fig. 6. When the shorter rivet is to be applied, as in the hole 48, 95 Fig. 1, the anvil head 50 is lifted a short distance and turned around on its axis through one hundred and eighty degrees whereby the projection 60 will abut the projection 63 end to end, as seen in Fig. 100 7, the anvil head being thereby raised the required amount. In order to maintain the anvil in this raised position I provide studs 67 and 68 on the screw 58 adapted to interfit with correspondingly placed holes 69 105 and 70 in the stem 57. By means of the screw 59 the anvil head 50 is raised or lowered so as to bring it in its desired relationship to the throw of the plunger and is then permanently secured in that 110 position by means of the locking nut 59. The other adjustment mentioned to provide for rivets of different lengths respectively is one which may be made easily and quickly as the repair work goes along. 115

When a brake band or the like requires relining the first operation is to remove the old lining, and I therefore provide for interchangeability of parts to enable the lining-removing operation to be performed 120 upon the same machine and in an easy and rapid way. Fig. 8 shows the insertion of a chisel 32 in the axial hole 30 in the end of the stem 17^a where it is held by the set screw 33. The chisel has a 125 sharp cutting edge at its lower end and the blade forces the fabric aside and cuts through the rivet as seen in Fig. 8. To hold the brake band in its edgewise position as shown by Fig. 8 for the rivet-cut- 130

ting operation I provide a special form of anvil 75 having an upstanding cheek 76 against which the band is held, the cheek being provided with a vertical recess 77 adapted to accommodate the head of the rivet, the brake band resting in a notch 78, the anvil 75 having a stem 79 adapted to fit into the hole 56 in the base 55. The anvil is held in its desired position by projections 80 engaging between them the projection 81 integral with the frame.

The principal use of the present device is in automobile repair shops, and since in such shops the repair work of all kinds is done by men who are not ordinarily skilled mechanics, the provision of a device which will enable such employees to reline brake bands and the like expeditiously and so as to produce a mechanically perfect job is highly important on various grounds, including the added safety to the occupants of the car in the strong and otherwise proper connection of the flexible part to the steel band.

25 I claim:

1. In a tool of the character described, the combination of a rigid upright frame having a lower forward extension and a medial forward extension, a vertically slideable plunger mounted in the medial extension, means on the lower extension for hold-

ing a riveting tool in line with the plunger, a hand lever pivotally mounted at the upper end of the frame and extending upward approximately vertically so as to be pulled upon first on approximately horizontal lines, said lever having a short arm extending forward substantially at right angles to the hand lever near the pivotal mounting, and a link connection between the plunger and said short arm, the lower end of the plunger having means for holding a cooperating riveting tool.

2. In a tool of the class described, the combination of a base having a hole therein adapted to receive the stem of an anvil, an anvil having a stem projecting loosely into said hole, an adjusting screw in the base coaxial with said hole, the end of the screw having a step construction providing a projection on one side thereof, the stem of the anvil having a step construction including a projection on one side thereof, the two step constructions substantially interfitting with each other with said projections side by side, the arrangement being such that by partially withdrawing the stem of the anvil and turning it on its axis the projections will abut each other end to end.

JAMES R. LEWIS.
